UNITED STATES PATENT OFFICE.

CHARLES KNOX HARDING, OF CHICAGO, ILLINOIS.

DESIGN FOR A LAMP-BURNER.

SPECIFICATION forming part of Design No. 31,406, dated August 15, 1899.

Application filed May 24, 1899. Serial No. 718,121. Term of patent 7 years.

To all whom it may concern:

Be it known that I, CHARLES KNOX HARDING, a citizen of the United States, residing in the city of Chicago, county of Cook, and 5 State of Illinois, have invented a new and useful Design for Hydrocarbon-Lamp Burners, of which the following is a specification, reference being had to the accompanying drawing, forming a part hereof.

10 In the drawing is shown in perspective a lamp-burner made in accordance with my design.

A lamp-burner made in accordance with my new design consists of a body or head having a central or axial opening which is made 15 upwardly flaring or larger at the upper end of the head than the lower end thereof. Said head is provided between its bottom and top walls with a relatively thick radial flange, 20 which surrounds the same. Depending from the lower wall of said head are two arms, which are united to the lower surface of said head external to the central opening therein. One of said arms is of greater length than the 25 other arm, and each arm is provided at its lower end with an inwardly-directed horizontal arm arranged radially with respect to the

central axis of the burner. The horizontal inwardly-directed arm of one of said depending arms is arranged horizontally above the 30 horizontal arm of said other depending arm. The horizontally-directed arm of the longer depending arm is provided with a depending cylindric part which is located concentrically with respect to the central axis of the burner, 35 and said horizontal arm is also provided with an axial cylindric extension projecting past the central axis of the burner. The horizontal radial arm connected with the shorter depending arm is provided in its upper surface with an opening in alinement with the central axis of the burner. 40

The main or characteristic features of my design are embraced in the arrangement and configuration of the several parts as above 45 described.

I claim as my invention—

The design for a lamp-burner, substantially as herein shown and described.

CHARLES KNOX HARDING.

In presence of—

C. CLARENCE POOLE,
WILLIAM T. HALL.
